MEANS FOR SECURING ATTACHMENTS TO
FLOOR MACHINESWalter S. Finnell, Elkhart, Ind., assignor to
Finnell System, Inc., a corporation of IndianaOriginal application July 29, 1939, Serial No.
287,331, now Patent No. 2,281,278, dated April
28, 1942. Divided and this application November
22, 1941, Serial No. 420,061

7 Claims. (Cl. 287—53)

This invention relates to improvements in means for securing attachments to floor machines of the general type shown in United States Patent No. 1,881,431 dated October 11, 1932, to W. S. Finnell, entitled "Floor machine" in which an electric motor is employed to drive attachments such as rotary scrubbing brushes, sanders, and etc.

The present application is a division of application Serial Number 287,331, filed July 29, 1939, now United States Patent No. 2,281,278, dated April 28, 1942.

The principal object of the invention is to provide a floor machine or the like which includes a driving shaft to which attachments to be driven thereby may be quickly and easily attached and detached therefrom without the use of tools.

A further object of the invention is the provision, in a floor machine or the like, of attachments to be driven thereby which include center flanges having centrally mounted therein socket members which perform both the function of a socket member and of defining a slot in the center of the disc, the provision of a hairpin-like spring member extensions of which form locking ears. The said locking ears when pressed together permit the entire assembly to be snapped on to driving couplings which have tongue-like projections fitting such slots and which have a central depression adapted to be engaged by said locking ears.

Yet another object of the invention is the provision in attachments for floor machines of openings near the center of said attachments which permit cleaning material, water or wax to be fed downwardly through the revolving attachment when the device is in operation.

Other objects and advantages of this invention will be apparent from the following specification and drawing which show by way of example one embodiment of the invention.

Referring now to the drawing:

Figure 1 is a plan view of an attachment for a floor machine which in the present instance is a rotary brush, the central or hub portion carrying the new and improved attachment bushing;

Figure 2 is a sectional elevation, taken along the line 2—2 of Figure 1, wherein the attachment bushing is shown in cross section;

Figure 3 is a plan view of the hub of the attachment shown in Figure 1 and having a portion thereof broken away so that the spring may be more clearly seen;

Figure 4 is a sectional elevation taken along the line 4—4 of Figure 3, showing the tongue portion of the driving shaft positioned in the attachment bushing and the bushing being engaged by said spring; and

Figure 5 is a perspective view of the end of the driving shaft showing details of the tongue portion.

The rotary brush includes a disc 10 which carries a plurality of brush elements 24 extending from one face thereof and all terminating on a line, such as the line 26. The disc 10 has a plurality of spokes 11 which support a hub 10^b therein. Openings 34 formed between these spokes permit cleaning materials, rinsing water, wax, etc., to be fed downwardly through the revolving disc to the brush elements when the device is in operation.

Within the hub 10^b is formed a rectangular slot 30 which is centrally located with respect to the periphery of the disc 10. A socket member 29 is comprised of a disc-like member 12 having a rectangular hole formed therein and bounded by inwardly turned flat extensions 13 and 14, which fit in the opening 30 and form the long sides of the opening 30.

The disc 12, with its extensions 13 and 14, are preferably punched and form dies which accurately size the width of the opening between the extensions 13 and 14. The plate 12 is secured to the hub 10^b by means of bolts 15.

A spring 31, which has the general form of a hairpin, has its free ends looped to form lugs 31^a, 31^b, and is positioned on said hub with the legs of the hairpin spanning the opening 30. A plate 16 overlies the looped end of the spring 31 and is secured to the hub by means of a screw 17. In order that the spring 31 be permitted to flex freely, a depression 18 is formed in the body of the hub 10^b so that the head end of spring 31 may lie therein, and the plate 16 when secured to the hub by means of the screw 17 overlies the depression 18 and therewith forms a cavity within which the head end of the spring is positioned.

It is obvious that if the operator grasps the lugs 31^a, 31^b, with the thumb and fore-finger and presses these lugs together, the width of the portions spanning the slot 30 will be decreased as the lug ends are brought together.

Now, the member for driving the attachment (which is, of course, either driven directly by the motor or through gearing) carries a member 32 upon the end of which is formed a tongue 20 which is of a width to fit the slot 30.

In some instances the turned portions 13 and

14, especially when the member 12 is made of thin material, may be springy and so spaced that when the tongue 20 is inserted, a snug fit is obtained. The tongue portion 20 is widest where it joins the member 32 and narrowest at the points 21 bordering the slot 22, the surface therebetween being curved. Within the tongue 20 is formed a slot 23 which is substantially wider than the slot 22 and which communicates with the slot 23.

When the attachment is to be secured to the floor machine, the operator reaches underneath the attachment, through the opening between the brushes in the present instance as may be seen in Figure 2, and presses the lug portions 31^a, 31^b, of the spring together, and then registers the slot 30 with the tongue 20 and presses the attachment upwardly, as viewed in Figure 4, until the plate 12 abuts the face 32a of the driving member.

When this point is reached, the legs of the spring 31 (which has been pressed together by means of the lugs 31^a, 31^b) have passed through the slot 22 and are positioned in the slot 23 so that as soon as the operator releases the lugs 31^a, 31^b, the legs of the spring move oppositely or apart from each other and come to rest against the interior edges of the slot 23, whereupon the device is ready to operate.

When it is desired to remove the attachment from the machine, the operator grasps the lugs 31^a, 31^b, with the thumb and fore-finger, presses them together, and thereby brings the legs of the spring 31 near enough together to freely pass through the slot 22, whereupon the attachment may be removed.

Although I have herein shown and described a single embodiment of the invention by way of example, it is obvious that many changes may be made in the arrangement shown and described without departing from the spirit of the invention as set forth in the following claims.

What is claimed is:

1. In a floor machine, an attachment including a plate having a central aperture, a socket member secured to said plate and having portions forming side walls extending into said aperture, and a resilient member having laterally movable arms spanning said aperture below said socket member and secured to said plate whereby said attachment may be non-rotatably locked to a driving member and rotated thereby.

2. In a floor machine, an attachment including a plate having a rim portion and a central portion spaced apart from said rim, a socket member having a flanged head lying within said central portion of said plate and forming therewith a socket aperture extending therethrough, and locking means mounted adjacent said aperture and on the bottom of said plate whereby said attachment may be non-rotatably locked to a driving member and rotated thereby.

3. In a floor machine, an attachment including a circular plate having a laterally extending rim and a center portion lying within said rim and below the upper edge thereof, said center portion having a socket aperture there-

through adapted to receive a rotatable driving device, and means secured to the underside of said center portion of said plate for non-rotatably locking said plate to a driving device positioned in said socket.

4. In a floor machine, an attachment therefor having a hub portion, a rectangular hole therethrough forming a socket centrally located with respect to the axis of said hub, a spring generally U shaped and having its legs spanning said hole, means engaging the apex of said spring for securing the same to said hub, driving means on said machine including a tongue portion for co-operating with said socket, and means forming a transverse T slot in said tongue, whereby the legs of said spring may be squeezed together, said attachment may be applied to said machine with said rectangular hole engaging said tongue portion, and said spring legs released to engage said slot for locking said attachment on said tongue.

5. In a floor machine including a drive shaft having a tongue portion at the end thereof and having a transverse T slot formed in said tongue, an attachment therefor having a hub portion, a rectangular hole formed therethrough and forming a socket for said tongue, and a hair-pin shaped spring having its apex secured to said hub and its legs laterally spanning said rectangular hole, whereby said legs may be pressed together while said attachment is being applied to said tongue and thereafter released to engage the widest portion of said T slot for locking said attachment thereon.

6. In a floor machine including a drive shaft having a tongue portion at the end thereof and having a transverse T slot formed in said tongue, an attachment therefor having a hub portion, a rectangular hole formed therethrough, means secured to said hub portion and carrying strips positioned in said hole and overlying the long sides thereof, thereby forming a socket for said tongue, and a hair-pin shaped spring having its apex secured to said hub and its legs laterally spanning said rectangular hole, whereby said legs may be pressed together while said attachment is being applied to said tongue and thereafter released to engage the widest portion of said T slot for locking said attachment thereon.

7. In a floor machine including a drive shaft having a tongue portion at the end thereof and having a transverse T slot formed in said tongue, an attachment therefor having a hub portion, a rectangular hole formed therethrough, a plate detachably mounted on said hub and having inwardly turned extensions positioned in said hole and overlying the long sides thereof, thereby forming a socket for said tongue, and a hair-pin shaped spring having its apex secured to said hub and its legs laterally spanning said rectangular hole, whereby said legs may be pressed together while said attachment is being applied to said tongue and thereafter released to engage the widest portion of said T slot for locking said attachment thereon.
